UNITED STATES PATENT OFFICE

CALEB E. LEONARD, OF MIAMI, FLORIDA, ASSIGNOR TO LEONARD SPARK PLUG COMPANY, INCORPORATED, OF ST. PETERSBURG, FLORIDA, A CORPORATION OF FLORIDA

AVIATION PLUG

Application filed November 21, 1928. Serial No. 320,816.

My invention relates to ignition plugs for internal combustion engines, and its general object is to provide a structure which is exceptionally durable and efficient under the 5 severe conditions imposed by service in a high-pressure, or airplane cylinder, as well as under less severe conditions.

More particular objects are: To effectively radiate the heat from the central electrode; 10 to provide an improved gas tight connection of the insulator or insulators in the shell, which prevents gas leakage under high as well as ordinary pressures; and to provide a new and improved main electrode assembly. 15 In carrying out one of the principal objects above stated, namely, the cooling of the main or central electrode, I provide an outer or upper electrode member which is tubular and provided an opening to atmosphere, together with a heat conducting and radiating element within such tubular electrode which is in heat conductive connection with the main electrode and which rapidly conveys therefrom to the chamber of the tubular electrode, this heat being dissipated therefrom to atmosphere. 25

The stated features reduce strains upon the insulators, such as are ordinarily occasioned by undue heating and expansion of the central electrode, and increase the durability and efficiency of the plug in various other ways.

The present invention is similar in some respects to that disclosed in my companion 35 application, executed on even date herewith; but in the present case the general object is to adapt the plug for even more severe service, such as in airplane engines, where the pressure and heating effects may be extreme. 40 To withstand these stresses and provide electrical and mechanical efficiency, long life and dependability, I provide a lower insulating member of highly refractory material, such as quartz, and an upper insulator which 45 has more mechanical elasticity and is therefore better able to withstand mechanical stresses, such, for example, as laminated mica.

The characteristics and advantages of the 50 invention are further sufficiently explained

in connection with the following detail description of the accompanying drawings, which shows one preferred embodiment. After considering this example, skilled persons will understand that many variations 55 may be made, and I contemplate the employment of any structures that are properly within the scope of the appended claims.

In the drawings:

Fig. 1 is a longitudinal section of a spark 60 plug embodying the invention in one form.

Fig. 2 is a bottom plan.

Fig. 3 is a side elevation of separated electrode members, some parts being in section.

Fig. 4 is a side elevation of the lower, 65 or quartz, insulator.

The shell 1 may be of ordinary construction, except as hereinafter specified. It is formed at an intermediate part of its length with a sealing chamber having a cylindrical wall 2 terminating in a horizontal bottom shoulder 3. Above this chamber the shell is internally threaded as at 4. The lower insulator 5, which is preferably of highly refractory material, such, for example, as 70 quartz (or fused quartz), has oppositely arranged or tapering outer conical surfaces 6, the bases of the cones abutting at the line 7. A short upper portion of this insulator is cylindrical, as at 8. This insulator is secured and sealed in the shell by identical upper and lower gaskets 9 of compressible material such as copper, arranged in relatively reversed positions, and having inner 75 conical surfaces cooperating with the cone 80 surface 6, and outer cylindrical surfaces cooperating with the cylindrical wall of the sealing chamber. The gaskets are compressed to form a perfectly gas-tight seal, by a ring nut 10 having an external thread 90 engaging the shell thread 4 and having its lower end formed to engage the upper gasket and so to compress both of the gaskets. This nut or screw ring has in its upper face, sockets 11 to receive a spanner or other suitable tool to 95 tighten it in position.

The upper or outer insulator 12, which is preferably of laminated mica, or other material better able to resist mechanical shocks, is preferably assembled as a unit with the 100

central electrode structure, so that the upper insulator and electrode may be removed together without disturbing the lower insulator; also, the central electrode structure 5 is desirably assembled as a unit, as will also appear.

The central electrode structure comprises a main or lower electrode 13 of substantial diameter inserted with a tight press fit in the 10 lower end of a conducting sleeve 14, which may in some cases be of highly conductive material, such as brass or copper, or may, if desired, be of other metal. The sleeve 14 is desirably enclosed in a tubular wrapping 15 of mica to reduce electrical and gas leak effects, the laminations of the main laminated body 12 being internally diametered to fit above the sleeve. The laminations of the main body are compressed between a nut 16 20 engaging a thread 17 on the upper end of the sleeve 14, and a metal washer 18 in threaded engagement with the lower end of sleeve 14. Washer 18 preferably rests on a compressible gasket 19 which, in turn, is seated on an internal transverse shoulder 20 of the lower insulator. At its lower end, the upper insulator has an extension 12^a, entering the cylindrical bore of the lower insulator, and having its lower end engaging the upper 30 face of washer 18.

The upper insulator 12 is desirably formed with a shoulder at 21, and a compressible gasket 22 is located between this and the upper end of the locking or screw ring 10 to 35 form a gas-tight seal. Below shoulder 21 the insulator 12 has a cylindrical surface 23 of the same diameter as surface 8 of the lower insulator and desirably an insulating sleeve 24 of mica is wrapped about these surfaces, fitting within the inner bore of the screw ring 10.

A heat radiating rod or wire 30, which is preferably of small diameter and made of a highly conductive material, such as brass, 45 copper or bronze, but otherwise may be of other material, is inserted with a tight press fit in a hole in the upper end of the main or lower electrode 13, and this radiating member preferably extends through a greater part 50 of the length of the sleeve 14, which is open at its upper end and acts as a radiating chamber. Desirably rod 30 is of waved or sinuous formation to increase its effective radiating length.

Desirably a shoulder is formed as at 35, Fig. 1, in the upper insulator a short distance above bushing 25, thus reducing or preventing spark-jumping from the shell or bushing to the central electrode structure.

The central structure, including the upper insulator and connected parts, is secured in position by a bushing 25 screwed into the upper end of the shell and having an internal flange 26 engaging a shoulder 27 on insula- 65 tor 12, by which shoulder 21 is located down

on the compressible gasket 22, the lower end of the bushing also seating against this gasket.

Any suitable lower or grounded electrode may be provided. Preferably this is in the 70 form of a strip or block 40 bridging the lower or sparking chamber 41 of the shell and secured positively against any loosening or falling out by having its ends engaged in undercut sockets, or an annular channel 42 in the shell bore. The actual sparking element is a raised member 43 on the upper face of the block, in properly spaced relation to the lower end of the main electrode 13. 75

The central electrode structure, including 80 the members 14, 18, 13 and 30, is, as above explained, a practically unitary structure, the parts being in tight heat conducting contact. In operation, therefore, heat is rapidly conducted away from the lower electrode by sleeve 14 and by it radiated to air within the sleeve, and more especially heat is effectively conducted from the lower electrode by the radiating wire 30 and radiated from it to air within the sleeve, and so to atmosphere 85 through the open upper end of the sleeve, thus keeping the electrode structure at a desirable low temperature and preventing excessive strains upon the insulators. The 90 entire central structure, except the lower insulator 5, may be removed as a unit and replaced, by the removal of the bushing.

In some cases the adjacent edges of gaskets 9 may approximately or closely meet, when compressed, to increase the "tightness" of the 100 gas seal at this point.

Also, the main electrode 13, sleeve 14, and disc (or nut) 18, may be welded together, for greater mechanical strength and to increase heat-conductivity. 105

I claim:

1. In a spark plug, a central structure comprising an insulator, a metal sleeve therein open to atmosphere at its upper end, and a lower electrode tightly engaged in the lower 110 end of the sleeve, and a radiating rod in conductive connection with the upper end of the lower insulator and extending upwardly within the sleeve whereby heat is conducted from the electrode and dissipated to air within the sleeve and so to atmosphere. 115

2. In a spark plug, a central structure comprising an insulator, a metal sleeve therein open to atmosphere at its upper end, and a lower electrode tightly engaged in the lower 120 end of the sleeve, and a radiating rod of waved formation and of small diameter in conductive connection with the upper end of the lower insulator and extending upwardly within the sleeve whereby heat is conducted from the electrode and dissipated to air within the sleeve and so to atmosphere. 125

3. In a spark plug, a substantially unitary central electrode structure comprising a sleeve open to atmosphere at its outward 130

end, and an electrode tightly inserted in one end thereof, and a radiating wire tightly inserted in the electrode and extending within the sleeve.

5 4. In a spark plug, in combination with the shell and insulator, a central electrode structure comprising a lower, solid electrode portion and an upper tubular conducting portion having close heat conducting connection to the lower portion and open to atmosphere at its upper end, and a radiating rod of smaller diameter than said tubular portion and located therein and having close heat conductive connection to the lower electrode portion.

10 5. In a spark plug, in combination with the shell and insulator, a central electrode structure comprising a lower, solid electrode portion and an upper tubular conducting portion having close heat conducting connection to the lower portion and open to atmosphere at its upper end, and a radiating rod of smaller diameter than said tubular portion and located therein and having close heat conductive connection to the lower electrode portion, the radiating rod being in sinuous formation.

15 6. In a spark plug, in combination with the shell and insulator, a central electrode structure comprising a lower, solid electrode portion and an upper tubular conducting portion having close heat conducting connection to the lower portion and open to atmosphere at its upper end, and a radiating rod of smaller diameter than said tubular portion and located therein and having close heat conductive connection to the lower electrode portion, said radiating rod extending through a large part of the length of said tubular portion.

In testimony whereof I affix my signature.
CALEB E. LEONARD.
